US00D822599S

(12) **United States Design Patent** (10) **Patent No.:** **US D822,599 S**
(45) **Date of Patent:** **** Jul. 10, 2018**

(54) **PORTABLE POWER BANK**

(71) Applicant: **Shenzhen Ruimaide Technology Co., Ltd.**, Shenzhen (CN)

(72) Inventor: **Decai Zhong**, Shenzhen (CN)

(73) Assignee: **Shenzhen Ruimaide Technology Co., Ltd.**, Shenzhen (CN)

(**) Term: **15 Years**

(21) Appl. No.: **29/616,708**

(22) Filed: **Sep. 8, 2017**

(51) LOC (11) Cl. **13-02**

(52) U.S. Cl.

USPC **D13/108; D13/103**

(58) **Field of Classification Search**

USPC D13/102–110, 118, 119, 184, 199;
D14/356, 432

See application file for complete search history.

(57) **CLAIM**

The ornamental design for a portable power bank, as shown and described.

DESCRIPTION

FIG. 1 is a perspective view of a portable power bank showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof; and,

FIG. 7 is a bottom plan view thereof.

The broken lines in the drawings illustrate portions of the portable power bank which form no part of the claimed design.
